SHOE BOTTOM IRONING DEVICE

Ferman N. Lee, Danvers, Mass., assignor to
United Shoe Machinery Corporation, Flem-
ington, N. J., a corporation of New Jersey

Application January 29, 1952, Serial No. 268,715

18 Claims. (Cl. 12—51)

1

This invention relates to shoe-bottom ironing and is particularly concerned with the provision of a novel and improved device for applying heat and pressure to the lasted margin of upper materials along selected portions of the bottom of a shoe.

In the manufacture of shoes in which the lasted margin of the upper extends inwardly over the insole in substantially parallel relation to the bottom of the shoe, it has become a common practice to subject the overlaid lasted margin of the upper to heat and to pressure, directed both heightwise of the shoe and inwardly from the edge of the shoe bottom, to flatten the lasted margin of the upper evenly and to iron it smooth on the insole before the outsole is placed on the bottom of the shoe. A machine for performing this so-called "lasted-bottom ironing" operation is disclosed in United States Letters Patent No. 2,175,474, issued on October 10, 1939, in the name of Axel A. Lawson. As is explained in the Lawson patent, the ironing unit of the machine illustrated therein is adapted to operate on the lasted margin of the upper over the entire shoe bottom. However, such extensive shoe-bottom ironing may not be necessary, for example, if the lasted margin of the upper is adequately flattened and ironed, from the toe end of the shoe back to, or slightly beyond the ball portion, during the lasting of the toe and forepart of the shoe in certain types of lasting machines. Thus, the heated wipers of the lasting machine illustrated in United States Letters Patent 2,469,467, issued on May 10, 1949, in the name of Bernhardt Jorgensen, will function to flatten and iron the lasted margin of the upper along the forepart at the opposite sides of the shoe, while the toe-lasting machine may be provided with an auxiliary toe pressing apparatus of the type illustrated in United States Letters Patent 2,437,696, issued on March 16, 1948, in the name of Bernhardt Jorgensen which will flatten and iron the lasted margin of the upper at the toe end of the shoe. When shoes are prepared in the above manner, it is necessary only to flatten and iron the lasted margin of the upper at the heel end of the shoe and forwardly therefrom, at the opposite sides of the shank of the shoe, to the ball portion.

It is, therefore, an object of this invention to provide a novel and improved device for use in bottom ironing which is adapted to operate from the heel end of the shoe forwardly, through the shank, to the ball portion. Thus, in accordance with a feature of the invention, the herein illustrated device comprises a block provided with a

5 generally flat operating surface adapted to iron the lasted margin of the upper around the heel-seat portion of the shoe, and two sets of articulated shank-ironing members, hinged to said block and each shaped to present a curved operating surface adapted to iron the lasted margin of the upper at the opposite sides of the shank portion of the shoe. Preferably, and as herein illustrated, the ironing device is supported for pivotal movement as a unit, in order that the generally flat operating surface of the heel-ironing block and the curved operating surfaces of the articulated shank-ironing members may conform generally to the shape of the heel seat and shank portions of a shoe as the bottom of the shoe is brought into contact with the device. Also, the articulated shank-ironing members are connected together and to the heel ironing block by means of a series of equalizing levers which permit relative movement between the shank-ironing members and the heel-ironing block so that the ironing pressure is equally distributed over the entire heel seat and along the shank portion of the shoe, when the shoe is forced 10 against the ironing device. Associated with the aforementioned equalizing levers and the heel-ironing block and the sets of articulated shank-ironing members are coil springs which tend to swing the articulated members about their hinged connection to the heel block in directions to cause their curved operating surfaces to assume a minimum radius of curvature which is somewhat smaller than the radius of curvature of the steepest shank portion to be ironed. Thus, as the heel end and shank portion of a shoe are brought 15 into contact with the operating surfaces of the device, the articulated shank-pressing members will be swung about their pivotal connection to each other and about their hinged connection to the heel-ironing block and thereby caused to conform to the shape of the shank portion of the shoe.

Preferably, and in accordance with a further feature of the invention, the sets of articulated shank-ironing members are hinged to the heel-ironing block, adjacent to one edge of its operating surface, for pivotal movement about axes which are angularly disposed in such a manner that, as these sets of articulated members pivot thereabout, to conform to the shape of the shank portion of a shoe, they move toward each other. Hence, when the heel seat and shank portion of a shoe are brought into contact with and forced against the operating surface of the heel-ironing block and the operating surfaces of the

two sets of articulated shank-ironing members, the operating surfaces of the latter, as they move toward each other, will apply pressure to the lasted margin of the upper and the shank portion of the shoe which is directed both heightwise of the shoe and inwardly from the edge of the shoe bottom. Also, because of the angular disposition of their pivotal axes, the operating surfaces of the shank-ironing members are inclined upwardly and inwardly, relatively to the marginal edges of the shank portion of the shoe, and the generally flat operating surface of the heel-ironing block is similarly shaped, or "dished." Thus, when ironing pressure is applied to the lasted margin of the upper a wedging action is set up which tends to urge the upper materials inwardly from the edge of the shoe bottom. To facilitate their ironing actions, the heel-ironing block and the sets of articulated shank-ironing members are heated by means of electrical heating units installed directly therein.

The above and other objects and features of the invention will appear in the following detailed description of the preferred embodiment illustrated in the accompanying drawings and will be pointed out in the claims.

In the drawings,

Fig. 1 is a view in side elevation of a portion of a machine for ironing the bottoms of shoes provided with an ironing device embodying the features of this invention;

Fig. 2 is a view similar to Fig. 1 but showing only a portion of the machine at an enlarged scale;

Fig. 3 is a view similar to Fig. 2 but showing the ironing device operating on the bottom of a shoe;

Fig. 4 is a plan view of the ironing device with certain parts shown in horizontal section substantially on line IV—IV of Fig. 2 and looking in the direction of the arrows;

Fig. 5 is a view in vertical section substantially on line V—V of Fig. 2 and looking in the direction of the arrows; and

Fig. 6 is a view in end elevation of certain of the operating elements of the ironing device with one of those elements shown in vertical section substantially on line VI—VI of Fig. 2 and looking in the direction of the arrows.

Referring to these drawings, and particularly to Fig. 1 thereof, the ironing device, indicated generally by the reference character 10, is illustrated as associated with a shoe-bottom ironing machine which is operated by fluid under pressure. This machine has a fabricated shelf, or platform, 12 supported at a convenient height in any desired manner, on which there are mounted four upwardly extending posts 14, 14. Secured to the upper ends of these posts is a plate 16 on which the ironing device is supported. Projecting downwardly from this plate are two side flanges 18, 18 and a central flange 20, Fig. 4, the side flanges each having an ear portion 22, Figs. 2, 3 and 4. The ironing device comprises a heel-ironing block 24, having a generally flat operating surface 26, and hinged to the heel-carrying block, adjacent to one edge of its operating surface, are two sets of shank-ironing members each including a pair of hinged-together, or articulated, blocks 28, 30. The blocks 28, 30 are provided, respectively, with curved operating surfaces 32, 34 which form continuations of the operating surface 26 of the heel-ironing block. The heel-ironing block is pivotally mounted on a cross shaft 36, carried by the ear portions 22, 22 of the side flanges 18, 18. Each of the blocks 28 is hinged to

the heel-ironing block 24 by means of an integrally formed trunnion 40 which is journaled in a cylindrical recess 42 in the heel block, see Fig. 5, and is held in place by the keeper screw 44, Figs. 5 and 3, while each of the blocks 30 is hinged to its companion block 28 by means of an integrally formed trunnion 46, which is journaled in a bore 48 in the block 28 and is held in place by a keeper screw 50, Fig. 6.

Pivotedly mounted on a pin 52, which extends through the flanges 18, 18 and 20, are two equalizing levers 54, 54. On their left-hand ends, as viewed in Figs. 1, 2 and 3, these levers engage the opposite ends of an equalizing lever 56 which is pivotally mounted on an upstanding web 58 formed on the heel-ironing block 24. Journaled on pins 60, 60 mounted in the right-hand ends of the levers 54, 54 are two relatively short equalizing levers 62, 62, each provided, at its opposite ends, with adjustable abutment screws 64, 66 which are adapted to bear, respectively, against the upper ends of the blocks 28, 30, Figs. 2, 3 and 4. Coil springs 70, 72 and 74, stretched between pins mounted in the flanges 18, 18 in the opposite sides of the heel block 24 and in the outer sides of the blocks 28 and 30, tend to hold the several blocks of the ironing device yieldingly in the positions in which they are shown in Figs. 1 and 2. However, as will presently appear, when the bottom of a shoe S is pressed against the ironing device, these several blocks will be swung about their respective pivot points to an extent determined by the shape of the heel seat and shank portions of the shoe.

Referring to Fig. 1, the fluid-pressure-operated mechanism for pressing the bottom of a shoe against the ironing device comprises a large piston 80, mounted in a cylinder 82, and a small piston, or plunger 84. The cylinder 82 is bolted to a table 86 which is movably supported, between the posts 14, 14, on a series of rollers 88, 88 carried by the platform, or shelf, 12. The piston 80 has a piston rod 90 which extends upwardly through a cover plate 92, secured to the upper end of the cylinder 82, while the lower end of this cylinder is closed by a filler block 94 which rests on the table 86. This filler block is provided with a centrally located boss 95 and bore 96 in which the plunger 84 is received, and with an off-center port 98. A pair of flexible conduits 100, 102, are secured to the table 86 and are in communication, respectively, with the bore 96 and the port 98.

Extending through the piston 80 is an opening 104 with which there is associated a check valve 106, arranged to permit the flow of fluid downwardly through the opening 104 and to prevent the flow of fluid through the piston in a reverse direction. A coil spring 108 tends to hold the piston 80 in the lowered position in which it is shown in Fig. 1 and resting against the boss 95. Near its upper end, the cylinder 82 has an inlet port 110 and an outlet port 112 and connected to the inlet port is a conduit 114 which leads to a suitable source of fluid supply, not shown, to keep the cylinder 82 filled to the level determined by the outlet port 112. The conduits 100 and 102 are connected respectively to a source of fluid under pressure, not shown, and suitable valves, not shown, are provided for controlling the flow of fluid under pressure into, and exhaust from, these conduits. As will be apparent, when fluid under pressure is admitted to the conduit 100, the plunger 84 will be elevated, together with the piston 80 and the piston rod 90, under a relatively light force due to the small area of this plunger.

As the piston 80 is thus moved upwardly, the check valve 106 will open to permit the transfer of fluid through the opening 104 so that the space beneath the piston 80 is kept full of fluid. Now, when fluid under pressure is admitted to the conduit 102, the piston 80 and piston rod 90 will be moved upwardly under a considerably greater force due to the large area of the piston 80. Subsequently, when these two conduits are connected to exhaust, the spring 108 will return the parts to the positions in which they are shown in Fig. 1.

Supported on the upper end of the piston rod 90 is a bracket 120 on which there is pivotally mounted, by means of a pin 121, an intermediate member 122, see Figs. 2 and 3. Fitted in an arcuate recess 124, formed in the intermediate member, is a block 126 having an arcuate side 128 which is slideable in the recess 124 to the extent permitted by a pin 130, carried by the intermediate member 122 and passing through a slot 132 in the block 126. Projecting upwardly from the block 126 is a relatively short last pin 134. As will be apparent, when a shoe on its last is placed on the block 126, with the last pin 134 entering into the hole in the last, the shoe may be rocked about any one of three axes extending, respectively, heightwise, transversely and lengthwise of the shoe. Also, the shoe may be displaced in a rectilinear path, generally parallel to its length, and thus positioned relatively to the ironing device 10, by causing the table 86, and the parts carried thereby, to move along on the rollers 88, 88. However, when the shoe is released by the operator, it will, unless otherwise restrained, as by being pressed against the ironing device, fall into a receiving trough 140 which is mounted between the two posts 14, 14.

In using the machine which has just been described, the operator places a lasted shoe S on the block 126 and causes fluid under pressure to be admitted to the conduit 100. As the piston 80, piston rod 90 and the shoe S are elevated by the plunger 84, and as the heel seat and shank portion of the bottom of the shoe approach the operating surfaces 26, 32 and 34 of the heel-ironing block and the shank-ironing members, see Fig. 2, the operator displaces the shoe in a lengthwise direction to position it relatively to the ironing device and, if necessary, also swings, or rocks, the shoe, to level its heel seat and shank portion with respect to the aforementioned operating surfaces just before these parts are brought into contact therewith under a relatively light pressure. Next, the operator causes fluid under pressure to be admitted to the conduit 102 so that the heel seat and shank portion of the shoe bottom are pressed very firmly against the operating surfaces 28, 32 and 34 of the ironing device under the relatively high pressure provided by the piston 80, Fig. 3. After the shoe has been subjected to the ironing pressure for the desired period, the operator causes the conduits 100, 102 to be connected to exhaust and, as the piston 80 is moved downwardly by the spring 108, the shoe will fall into the receiving trough 140.

As has been explained above, the operating surfaces 32, 34 of the blocks 28 and 30 of each of the sets of shank-ironing members form curved operating surfaces which are continuations of the relatively flat operating surface 26 of the heel-ironing block 24. The operating surfaces 32, 34 of the blocks 28, 30 are so shaped, and the relative tensions of the springs 70, 72 and 74 are such that, before the heel seat and shank portions of a shoe have been brought into contact with the

ironing device, the blocks 28, 30 are swung in a counterclockwise direction, Figs. 2 and 3, relatively to the block 24, and the radius of curvature of the operating surfaces formed by these sets of blocks is somewhat less than the radius of curvature of the steepest shank portion to be handled. Also, the generally flat operating surface 26 of the heel-ironing block 24 is maintained in a generally horizontal position. Hence, just as soon as the heel seat and shank portions of a shoe are brought into contact with the ironing device, under the relatively light pressure provided by the plunger 84, the ironing device will rotate slightly as a unit until the operating surface 26 lies more or less flatly on the heel-seat portion and with the operating surfaces 32, 34 of the shank-ironing blocks 28, 30 conforming roughly to the shape of, but separated somewhat from, the shank portion of the shoe. Now, since the pivotal axis of the block 126 is horizontally offset from the axis of the shaft 36, when the shoe is forced against the ironing device under the higher pressure, produced by the piston 80, the heel block 24 will be rotated still farther and, through the actions of the equalizing levers, the articulated blocks 28, 30 will be swung, in clockwise directions, about their respective hinged connections to each other and to the heel-ironing block until the curved operating surfaces 32, 34 of the shank-ironing members are caused to conform very closely to the curved shank portion of the shoe. Inasmuch as the heel block 26 and the two sets of shank-ironing blocks 28, 30 are interconnected by means of the several equalizing levers 54, 54, 56, 62, 62, these blocks now function, in effect, like a rigid unitary block with a continuous unyielding operating surface which conforms substantially to the shape of the heel seat and shank portions of the shoe.

As will be apparent from Fig. 4, the cylindrical recesses 42, 42 which receive the trunnions 40, 40 of the blocks 28, 28, are angularly disposed in a horizontal plane. Also, as will be apparent from Fig. 5, these cylindrical recesses are angularly disposed in a vertical plane. Because of the angular disposition of these cylindrical recesses, when the shank-ironing blocks 28, 30 are swung about these trunnions, in a clockwise direction relatively to the heel-ironing block, Figs. 2 and 3, as the shank-ironing blocks are caused to conform to the shape of the shank portion of the shoe, these sets of shank-ironing members, i. e., the blocks 28, 30 will move slightly toward each other. Accordingly, in the shank portion of the shoe, the ironing device will apply pressure to the lasted margin of the upper on the bottom of the shoe which is directed both heightwise of the shoe and inwardly from the edge of the shoe bottom. Referring again to Figs. 5 and 6, it will be noted that, due to the inclination of the cylindrical recesses 42, 42, in a vertical plane, that the operating surfaces 32, 34 of the shank-ironing blocks 28, 30 are inclined out of the horizontal plane to conform generally to the transverse contour of the shoe bottom in the shank portion thereof. Similarly, the operating surface 26 of the heel-ironing block 24 is slightly "dished" as will be apparent from Fig. 5, to conform to the shape of the bottom of the shoe in the heel-seat portion thereof. Because of the inclinations of the operating surfaces 32, 34 and the "dished" shape of the operating surface 26, when the lasted margin of the upper is subjected to the relatively high pressure, a wedging action is produced which tends, in addition to the inward movements of the blocks 28, 30, to urge the lasting

margin of the upper inwardly toward the center of the bottom of the shoe. In connection with the above, it may be explained that when the expression "generally flat" is herein applied to the operating surface 26 of the heel-ironing block 24, it is used in a somewhat limited sense and is intended to distinguish the character of this generally flat operating surface from the operating surfaces 32, 34 of the shank-ironing blocks 28, 30, which have a pronounced lengthwise curvature.

In order to augment their ironing and smoothing actions, the heel-ironing block 24 and the shank-ironing blocks 28 and 30 are provided, respectively, with electrical heating units 150, 152 and 154. As will be understood, these heating units are connected to a suitable source of electrical energy, not shown, and are under the control of thermostatic devices for regulating the temperatures of the operating surfaces 26, 28 and 30.

Having described my invention, what I claim as new and desire to secure by Letters Patent of the United States is:

1. A device for use in ironing the shank and heel-seat portions of the bottoms of shoes comprising a heel-ironing block provided with a generally flat operating surface, two sets of shank-ironing members hinged to said ironing block, adjacent to one edge of its operating surface, each of said sets of shank-ironing members including a number of articulated blocks shaped to provide a curved operating surface forming a continuation of the operating surface of the heel-ironing block, and means associated with said heel-ironing block and said sets of shank-ironing members for causing the generally flat operating surface of the heel-ironing block and the curved operating surfaces of said sets of shank-ironing members to conform to the shape of the flat heel seat and curved shank portion of a shoe, in response to pressure of the shoe bottom against said surfaces.

2. A device for use in ironing the shank and heel-seat portions of the bottoms of shoes comprising a heel-ironing block provided with a generally flat operating surface, two sets of shank-ironing members hinged to said ironing block, adjacent to one edge of its operating surface, each of said sets of shank-ironing members including a pair of articulated blocks shaped to provide a curved operating surface forming a continuation of the operating surface of the heel-ironing block, means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces.

3. A device for use in ironing the shank and heel-seat portions of the bottoms of shoes comprising a heel-ironing block provided with a generally flat operating surface, two sets of shank-ironing members hinged to said ironing block, adjacent to one edge of its operating surface, each of said sets of shank-ironing members including a number of articulated blocks shaped to provide a curved operating surface forming a continuation of the operating surface of the heel-ironing block, and means including equalizing levers associated with said articulated blocks and with said sets of shank-ironing mem-

bers and said heel-ironing block for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces.

4. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface, each of said sets of shank-ironing members including a number of articulated blocks shaped to provide a curved operating surface forming a continuation of the operating surface of the heel-ironing block, and means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces.

5. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface, each of said sets of shank-ironing members including a pair of articulated blocks shaped to provide a curved operating surface forming a continuation of the operating surface of the heel-ironing block, and means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces.

6. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface, each of said sets of shank-ironing members including a pair of articulated blocks shaped to provide a curved operating surface forming a continuation of the operating surface of the heel-ironing block, and means including equalizing levers associated with said articulated blocks and with said sets of shank-ironing members and said heel-ironing block for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces.

7. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface,

forming a continuation of the operating surface of the heel-ironing block, means for supporting said device for pivotal movement as a unit, means including equalizing levers associated with said articulated blocks and with said sets of shank ironing members and said heel-ironing block for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces, and means for heating said heel-ironing block and the articulated blocks of said sets of shank-ironing members.

15. A device for use in ironing the shank and heel-seat portions of the bottoms of shoes comprising a heel-ironing block provided with a generally flat operating surface, two sets of shank-ironing members hinged to said ironing block, adjacent to one edge of its operating surface, each of said sets of shank-ironing members including a pair of articulated blocks shaped to provide a curved operating surface forming a continuation of the operating surface of the heel-ironing block, means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces, said curved operating surfaces of the shank ironing members being inclined upwardly and inwardly, relatively to the shank portion of the shoe, to produce a wedging action on the overlasted margin of the upper materials as the bottom of the shoe is pressed against said surfaces.

16. A device for use in ironing the shank and heel-seat portions of the bottoms of shoes comprising a heel-ironing block provided with a generally flat operating surface, two sets of shank-ironing members hinged to said ironing block, adjacent to one edge of its operating surface, each of said sets of shank-ironing members including a pair of articulated blocks shaped to provide a curved operating surface forming a continuation of the operating surface of the heel-ironing block, means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces, said generally flat operating surface on the heel-ironing block being inclined upwardly and inwardly, relatively to the

5 heel-seat portion of the shoe, and said curved operating surfaces on the shank-ironing members being inclined upwardly and inwardly, relatively to the shank portion of the shoe, to produce a wedging action on the overlasted margin of the upper materials as the bottom of the shoe is pressed against said surfaces.

10 17. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface, each of said sets of shank-ironing members including a number of articulated blocks shaped to provide a curved operating surface forming a continuation of the operating surface of the heel-ironing block, and means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces, said angularly disposed axes being so arranged that the curved operating surfaces on said shank-ironing members move toward each other as these surfaces are thus caused to conform to the shank portion of the shoe.

15 18. A device for use in ironing the shank and heel-seat portions of the bottoms of shoes comprising a heel-ironing block provided with a generally flat operating surface, two sets of shank-ironing members hinged to said ironing block for pivotal movement about angularly disposed axes, adjacent to one edge of its operating surface, each of said sets of shank-ironing members including a number of articulated blocks shaped to provide a curved operating surface forming a continuation of the operating surface of the heel-ironing block, and means associated with said heel-ironing block and said sets of shank-ironing members for causing the generally flat operating surface of the heel-ironing block and the curved operating surfaces on said sets of shank-ironing members to conform to the shape of the flat heel seat and curved shank portion of a shoe, in response to pressure of the shoe bottom against said surfaces, said angularly disposed axes being so arranged that the curved operating surfaces on said shank-ironing members are inclined upwardly and inwardly, relatively to the shank portion of the shoe, to produce a wedging action on the overlasted margin of the upper materials as the bottom of the shoe is pressed against said surfaces.
